UNITED STATES PATENT OFFICE

172,022

DISPLAY CABINET OR SIMILAR ARTICLE

Wallace W. Harwood, New York, N. Y., assignor to August Rust-Oppenheim, New York, N. Y.

Application October 21, 1952, Serial No. 21,918

Term of patent 14 years

(Cl. D80—11)

To all whom it may concern:

Be it known that I, Wallace W. Harwood, a citizen of the United States, residing at 875 Fifth Avenue, New York city, county of New York, State of New York, have invented a new, original, and ornamental Design for a Display Cabinet or Similar Article, of which the following is a specification, reference being had to the accompanying drawing, forming a part thereof, in which

Fig. 1 is a front plan view of a display cabinet or similar article, with the glass front panel removed, showing my new design;

Fig. 2 is a front perspective view; and

Fig. 3 is a rear perspective view thereof.

I claim:

The ornamental design for a display cabinet or similar article, as shown.
